Primary Examiner — Catherine S Posthauer*(74) Attorney, Agent, or Firm* — Fross Zelnick Lehrman & Sissu, P.C.; Lawrence E. Apolzon, Esq.(57) **CLAIM**

The ornamental design for a fragrance bottle cap, as shown and described.

DESCRIPTION

FIG. 1 is a front perspective view of a fragrance bottle cap showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is a front perspective view of the fragrance bottle cap shown in FIG. 1 in the environment of a bottle.

The broken lines are shown for the purpose of illustrating both parts of the article as well as environmental subject matter of an exemplary fragrance bottle. None of the broken lines form part of the claimed design.
